33 Claims. (Cl. 93—62)

This invention relates to a rotary machine for manufacturing, at choice, bags, pockets, double pockets and envelopes. In its narrower aspect the invention has reference to a machine, for the purpose specified and of the kind in which a sheet or blank which, for the time being, comes lowermost in a stack of sheets is bulged out between two oppositely rotating rolls and withdrawn from the stack while, at the same time, the bulge in the sheet is converted into a fold.

The most important feature of the invention is to be observed in the combination comprising a device which withdraws a sheet from the stack while, at the same time, giving it one fold and immediately thereafter gives it a second and parallel fold, a roll system, immediately adjoining said device, said roll system being operative to align the work-pieces, pre-crease the same for the remaining folds and (when necessary) stick together the two flaps first formed and an endless travelling conveying means provided with grippers which latter carry the work-pieces past means operative to fold over the two flaps still remaining open and to stick down one of these flaps and finally deliver the finished work-pieces to the output stack.

This combination, in itself, affords certain important advantages over known machines. Among such advantages may be mentioned the simplified construction of the machine and the facility afforded for supervising its several individual operating points and the progress of the work as a whole, but the most important advantage resides in the possibility which it affords for making up the most widely varied kinds of work-pieces, such as flat bags, pockets, double (folder) pockets and envelopes for letters in all the various shapes and with all the different types of sticking that may be adopted for such articles. To particularize; it is possible, owing to the use of the grippers arranged on the endless conveying means, for folding over the two flaps last formed, to make articles, for instance, envelopes of the five-seal type (with triangular flaps) in which the side flaps are very broad, extending to the middle of the work-piece or even farther. This is because the folding over of such flaps is in nowise hindered by the grippers as it is when conveyor rolls and cylinders are used.

The advantages of the combination according to the invention are greatly enhanced by novel constructions of individual devices therein. Thus, the devices now to be enumerated also constitute subject matter of this invention:

55 1. A device for withdrawing the lowermost

sheet from the stack and producing the first two parallel folds. For this purpose there are employed two pairs of rolls which co-operate in such a manner that the sheet is first seized by an intake roll and bulged out under the rest of the stack and then nipped between the said intake roll and a counter roll and drawn out from beneath the stack, with simultaneous formation of the first fold. The intake roll then holds the sheet fast, by suction, until the said sheet is engaged between it and the adjacent top roll of a second pair of rolls. The sheet, thus engaged, is guided into a pocket wherein the fold first formed in said sheet strikes against a stop, so adjusted that the after end of the sheet, still positively engaged and driven, is bulged out into the aforementioned second pair of rolls, between which the second fold is then produced. In this way it is ensured that the two folds first formed in the work-piece will be located exactly at the right distance apart, since, in contradistinction to the working of known devices, it is not the temporal separation of the two fold-forming operations which determines the distance apart of the two folds, but only the spatial separation of the aforesaid stop from the second pair of rolls.

Moreover, with the arrangement described, it is possible to give a very large diameter to the intake roll and a very small diameter to its two counter rolls. Since the circumference of the intake roll determines the maximum size of the sheet that can be drawn in by it per revolution, its large diameter has the advantage of affording great adaptability, that is to say, a wide difference between the largest and the smallest sizes of sheet that can be worked. The small diameter of the first of the counter rolls co-operating with the intake roll also reduces the space into which the sheet to be withdrawn has to be bulged out, so that the production of scrap at the sheet intake is avoided. Finally, the small diameter of the second counter roll ensures that, even when making flat bags, stuck at the side, so that one of the side flaps is very narrow, this side flap will still be engaged by the intake roll and its second counter roll when the second fold is formed, whereby, even in this case the fold is formed with absolute exactitude.

2. The intake roll as such. For the purpose of engaging the sheet it is provided with two devices which, having regard to the direction of rotation of the roll, lie one behind the other. The device that lies to the rear engages the sheet first, by the action of suction or friction,

10

15

20

45

50

55

and bulges it out, whereupon the forwardly located device seizes, by suction, the bulge formed in the sheet and directs it positively under the first counter roll where it is converted into the first fold. In this way unfailing introduction of the sheet between the intake roll and its first counter roll is ensured.

3. A rubber rail extending longitudinally at the periphery of the intake roll and serving as the rearwardly located sheet-engaging device, aforesaid. It is first to engage the sheet and bulge it out. Special means are employed to control this rubber rail in such a way that it emerges from the periphery of the roll, either 15 at every revolution of the latter or at every second revolution thereof, for the purpose of engaging the sheet. This device makes it possible to withdraw a sheet from the stack either at each revolution or at each second revolution of 20 the intake roll, so that, in conjunction with other measures, the number of smaller work-pieces that can be operated upon is twice the number of work-pieces of larger size for the same number of revolutions of the machine.

25 4. A device which is used in conjunction with the system of rolls employed in the combination to enable adhesive, for sticking together the two first formed and partially overlapping flaps, to be applied, if need be, to the undermost of these 30 two flaps. This last named provision is absolutely necessary, in view of the way in which the combination works. The device consists of a rotating adhesive applying rail and, located ahead of this, suction members which likewise rotate, 35 said rail and said suction members being so controlled that the latter raise the overlying flap and the adhesive applying rail passes beneath this flap to apply adhesive to the flap lying underneath, whereupon the said adhesive applying 40 rail moves out again from beneath the upper flap which the suction members then release. Meanwhile a supplementary device assists in freeing the lower flap from the adhesive applying rail.

45 5. Means serving for longitudinal adjustment in relation to the rest of the machine of the whole arrangement for withdrawing the sheet from the stack and producing the first two folds. This adjustability facilitates changing over the 50 machine from one size of work-piece to another.

One embodiment of the invention is shown, by way of example, in the accompanying drawings. In these drawings:—

Figs. 1 and 2, which are intended to be arranged in continuity, one beyond the other, in accordance with their terminal dot and dash lines, show a diagrammatic longitudinal section through the apparatus as a whole. More particularly, Fig. 1 includes the fold intake device 55 with the associated means for aligning and pre-creasing half-finished work-pieces, for applying the adhesive, for sticking the two first folded flaps together and for introducing the work-pieces into the rotating grippers, while in Fig. 2 is depicted 60 the part lying in the region of the gripper conveyor.

Fig. 3 is a vertical transverse section through an intake roll, showing a second form of construction for such member.

70 Fig. 4 is a fragmentary vertical longitudinal section through an intake roll, showing the course of the suction air.

Fig. 5 is a side elevation of a special control device for the rubber rail provided in the intake roll.

Fig. 6 is a vertical transverse section through the intake roll, showing the springing of the steel bar carrying the rubber rail.

Fig. 7 is a side view of the device for applying the adhesive for sticking the bag work-pieces 5 lengthwise.

Fig. 8 is a side view of a gripper and shows how it is arranged on a travelling chain, while

Fig. 9 is a front view of a gripper, looked at in the direction of the arrow in Fig. 8.

The stack of sheets 1 rests on the stack table 3 fixed over the side cheeks 2 and is maintained in its orderly condition by the adjustable stops 4.

Under the stack table 3 the intake roll 5, shown in the example of Fig. 1 as a combined friction 15 and suction roll, is mounted in the side cheeks 2 in such a manner that its periphery protrudes through a slot in the table 3 by a small amount.

The counter roll 6 for the intake roll 5 is yieldingly pressed against the latter and is mounted 20 in such a way that its periphery does actually project into the slot in the table but does not protrude above the top surface of the latter. In

25 a channel running axially in the intake roll 5 there rests a radially displaceable steel bar 7 in which is fixed a rubber rail 8. The steel bar 7 is pressed towards the middle point of the intake roll 5 by springs 9 (see Fig. 6). On the shaft 10, journaled in the end walls of the intake roll 5 are fixed two levers 11 (see Fig. 5), the free

30 ends of which bear upwardly from underneath against the steel bar 7. Moreover, the shaft 10 also carries a bowl lever 12, the bowl 13 of which runs on the cam disc 14. This latter is mounted loosely on the shaft 5' of the intake roll and it

35 consists of two discs of like profile which can be relatively displaced in such a manner that the raised stretch along the periphery of the cam may have either the minimum extent shown by the full lines or twice that length as shown 40 completed by the dotted line. The two parts of the cam disc 14 are secured in their relative positions by means of the screws 15. The spur

wheel 16 is fixedly attached by means of screws 45 17 to the under part of the cam disc 14 as seen in Fig. 5. An idler spur wheel 18 is engaged with the spur wheel 16 and is driven by the spur wheel 19 which, in turn, is driven from a suitable point

50 in the machine, in the direction of the arrow and in such a way that it makes the same number of revolutions as the intake roll 5. The spur wheel 16 has double as many teeth as the spur wheel 19. Accordingly it is apparent that half the number

55 of revolutions of the intake roll 5 can be transmitted to the spur wheel 16 and thus to the cam disc 14 the motion being in the direction of the arrow 14', which is also the direction of rotation of the said intake roll. The idler spur wheel 18 can be swung about the shaft 20 of the spur

60 wheel 19 and so brought out of engagement with the spur wheel 16 and it can be locked in this 55 swung out position by known means (not shown). Furthermore, the cam disc 14 can be locked by the arresting device 21 when the spur wheels 16

65 and 18 are not in engagement. If the cam disc 14 be locked by the arresting device 21, then at 60 each revolution of the intake roll, the steel bar 7 carrying the rubber rail 8 is temporarily moved

65 outward once in opposition to the action of the springs 9 (Fig. 6) and in accordance with the 70 raised path on the periphery of the cam disc 14, in such a way that the rubber rail 8 emerges

75 somewhat above the peripheral surface of the roll. If, on the contrary, the cam disc 14 be freed by the arresting device 21 and if the spur

75

70

75

wheels 16 and 18 be brought into engagement with each other, the movement of the steel bar 7 with the rubber rail 8 still takes place at the same point in its path of revolution but only at every 5 second revolution of the intake roll 5, since, in the same time, the cam disc 14 makes one revolution in the same direction as the roll 5. In the latter case, in order that the emergence of the rubber rail 8 above the peripheral surface of the 10 roll may not, in consequence of the cam disc 14 turning with the roll but half as fast, be allowed to last longer, the two parts of the cam disc are so adjusted relatively to one another that the raised stretch of the cam is only half as long as 15 when the cam disc is at rest.

The intake roll 5 has, in advance of the rubber rail 8, having regard to the direction of rotation of said roll, an axially directed suction duct 22, which is connected to a vacuum control device, 20 of known kind, by way of a longitudinal bore 23 (Fig. 4) in the roll shaft 5' and a fixed attachment 26 having a pipe coupling 24 for a pipe or hose connection 25, the vacuum control device being connected to a vacuum air pump and 25 neither of these two last named members being shown in the drawings. From the suction duct 22 suction openings 27 extend in an axial row to the peripheral surface of the roll.

In Fig. 3 is shown a constructional form of the 30 intake roll 5 in which, instead of the controllable rubber rail 8 a second axial row of suction openings 28 is provided, opening into a separate suction duct 29 and at the peripheral surface of the roll. In this construction the roll shaft 5' has 35 a longitudinal bore 23, as shown in Fig. 4, at each end, these longitudinal bores each leading by way of a fixed attachment to a separate vacuum control device and thence to the air pump.

With the intake roll 5 there co-operates a second counter roll 30 which, at the same time, constitutes the top roll for a roll 31. On the cross-bar 32 fixed to the side cheeks 2 are arranged a plurality of curved guides 33, side by side, which extend around the intake roll 5, between the 45 counter rolls 6 and 30, leaving a small free space or gap.

Below the intake roll 5, running off tangentially thereto and on an incline, a superimposed pair of rack-like guide rails 35 and 35' are attached 50 to flat iron bars 34 fixed between the side cheeks 2, these rails being separated from each other sufficiently for a work piece to be able to run in between them comfortably. A stop rail 37, adjustable by means of a screw 36, extends into the 55 gap between the guide rails 35, 35', so that a work-piece running in between the latter strikes against the stop rail 37 and is prevented from running any further. The guide rails 35, 35', together with the stop rail 37 form a so-called 60 impact folder pocket.

All the parts described so far belong to the fold intake device and are connected, directly or indirectly, with the side cheeks 2. These latter are horizontally adjustable in the longitudinal direction of the side cheeks 38 of the rest of the machine. For their adjustment there is provided a shaft 39, which is journaled in them and on which are fixed two spur wheels 40 each of which engages in a toothed rack 41, these racks being fitted each to one of the side cheeks 38, so that 65 rotating the shaft 39 results in shifting the side cheeks 2 in one direction or the other. Known devices (not shown) are used for locking the side cheeks 2.

The two rolls 30 and 31 form the first pair of 70

rolls in a horizontal roll track comprising the pairs of rolls 42, 43; 44, 45; 46, 47; 48, 49; 50, 51 and 52, 53. The individual rolls in this roll track are formed in various different ways according to the functions assigned to them in the treatment 5 of the work-pieces. The pair of rolls 30, 31 takes over the work-piece which is in the impact folder pocket, consisting of the parts 35, 35', 36 and 37 and forms a second fold. The roll 31 is formed as a suction roll, but the purpose of making it 10 so is of no importance so far as the present invention is concerned. The work-piece now comes between the pair of rolls 42, 43, of which the roll 42 has two sheet steel rails 54, projecting slightly above its peripheral surface and as this 15 roll rotates these rails encounter a longitudinal groove 55 in the counter roll 43 the diameter of which is half the size of that of the roll 42. As will be explained later, the sheet steel rails 54 serve for aligning the work-pieces. The following 20 pair of rolls, 44, 45 is simply a pair of conveyor rolls, as also are the pairs of rolls 48, 49 and 52, 53. The pair of rolls 46, 47 takes care of the pre-creasing of the work-piece for the succeeding folding operations. The bottom roll 47 25 has a rubber coating 56, into which the breaker knives or pre-folder blades 57 and 58 on the roll 46 press lightly. The pre-folder blades 57 and 58 are fixed to individual longitudinally adjustable parts of which the roll 46 is built up. The folds 30 running in the direction in which the work-piece is being conveyed are pre-creased by the circular plate-like blades 57 while those which run at right angles to that direction are pre-creased by the axially arranged blade 58. The blade 58 as is 35 further explained hereinafter is used only in the production of certain kinds of work-pieces.

After the work-piece has run through the pair of rolls 48, 49 the adhesive for the longitudinal sticking of flat bags is applied between the pair 40 of rolls 50, 51. Since that flap of the bag which lies underneath and to the rear, having regard to the direction of travel of the work-pieces has to receive the adhesive, it becomes necessary for the adhesive applying rail by means of which the 45 adhesive is applied to be brought underneath the already turned up top flap, which lies advanced in the direction of travel and, likewise, for it to be able to emerge again from beneath the said top flap. In order to permit of this, the top roll 50 50 is constructed in the following manner:—

The actual conveying of the work-piece is effected by two discs 60 adjustable longitudinally of the roll shaft 59, these discs being provided with diametrically opposed lugs or projections 61 55 directed towards the middle of the roll. Only these lugs 61 come into contact with the work-piece for the purpose of causing the same to travel. They only engage the lower and rearwardly lying flap W' at those opposite ends 60 thereof which lie transversely of the direction of travel and this they do outside the region of the turned up top flap W'. As regards the said flaps of the work-piece, attention is directed to Fig. 7 in which, however, for the sake of clearness, the discs 60 with the lugs 61 are not shown. On the roll shaft 59 double-armed members 63 are fixed by means of screws 62, these members carrying the adhesive applying rails 64, both of which can be seen in Fig. 1, while in Fig. 7 only 70 one is shown. In addition, a plurality of double-armed members 65 are fixedly arranged on the roll shaft 59, each arm of these being formed as a suction member and, to this end, provided with bores 66, these bores presenting suction openings 75

at the outer ends of the arms while in the interior, they are connected with longitudinal bores 67 in the roll shaft 59, serving as suction ducts. These separate longitudinal bores 67, like those 5 in the roll shaft 59 are connected each by way of a vacuum control device, to a vacuum air pump. Finally, a toothed segment 68 is fixed by means of a screw 69 to the roll shaft 59.

A spur wheel 70, driven from any suitable point 10 in the machine is used to drive the roll shaft 59. The spur wheel 70, however, is not made fast on the roll shaft 59, but is loosely rotatable thereon and is coupled thereto solely by a toothed segment 71. This toothed segment 71 is rotatable about 15 a stud 71' screwed into the spur wheel 70 and engages with the toothed segment 68 mounted on the roll shaft 59. Accordingly, the roll shaft 59 is entrained by the spur wheel 70 through the intermediary of the two toothed segments 68 and 20 71 and if the toothed segment 71 be partially rotated about the stud 71', the roll shaft 59 executes a corresponding movement and so becomes displaced relatively to the driving wheel 70. The toothed segment 71 carries a bowl arm, the bowl 25 72 of which is pressed against a fixed cam disc 74 by a spring 73. Consequently, when the driving wheel 70 is rotating, so long as the toothed segment 71 is not swung out of place the roll shaft 59 revolves with the same angular velocity 30 as the driving wheel 70, so that the outer ends of the adhesive rails 64 and the suction members 65 have a peripheral velocity which agrees exactly with the velocity of travel of the work-piece W. When, however, the bowl 72 of the 35 toothed segment 71 is riding up to the high point of the cam disc 74 this produces rotary displacement of the roll shaft 59 relatively to the spur wheel 70 and so causes the peripheral velocity of the adhesive rails 64 and of the suction members 40 65 temporarily to become greater than the velocity of travel of the work-piece W. On the contrary, when the bowl 72 of the toothed segment 71 is riding down from the high point of the cam disc 74, the peripheral velocity of the 45 adhesive rails 64 and of the suction members 65 is less than the velocity of travel of the work-piece W.

Simultaneously with the inception of its increased peripheral velocity or immediately thereafter, the operative suction members 65, under the action of the vacuum control device connected thereto seizes the forward and upper flap W' of the work-piece W and bends it upwards, so that the adhesive rail 64 following directly 55 behind can reach under this flap on to the subjacent flap W'' and apply adhesive to the latter. If now, after the adhesive has been applied and the adhesive rail 64 has freed itself from the work-piece W, retardation of the peripheral velocity of the said adhesive rail 64 and of the suction members 65 sets in and if, at the same time, the suction effect in the said suction members be terminated, the adhesive rail 64 will again emerge from underneath the upper flap W' and 60 this latter will lie down again on top of the lower flap W''.

To assist and accelerate disengagement of the adhesive rail 64 from the work-piece, a plurality of sheet metal flaps 75 are pivoted on two diametrically opposite shafts 76 so as to be movable in the longitudinal direction thereof. In Fig. 7 only one of these is represented. The shafts 76 are mounted in double-armed members, likewise not shown but which, like the parts 63 and 65, 65 75 are screwed on to the roll shaft 59 and, conse-

quently, partake in the transitory increase and decrease in its peripheral velocity. Upon the shaft 76 is also fixed a bowl lever, the bowl of which is pressed by a spring 77 against a fixed cam disc 78, only indicated in Fig. 7, the effect 5 of this cam disc being to swing the sheet metal flaps 75, at a given moment, out of the position shown in full lines and into that shown in dotted lines, so that they press the lower flap W'' of the work-piece away from the adhesive rail 64. 10 The adhesive rails 64 are fed from the adhesive container 80 through the intermediary of the dipper roll 81 and the applicator roll 82.

The pair of rolls 52, 53, being the last pair of the roll track, is adapted to pass the work 15 pieces on to the grippers 83 of one or more chains 84. In the drawings one such chain is shown. Upon this the grippers 83 are fastened at definite and inter se equal distances. The chain 84 runs over the chain wheels 85, 86, 87 (see also 20 Fig. 2). Each of the grippers 83 is so fitted into the chain that the bottom or basic member 88 thereof (Fig. 8) at the same time forms an outer member of the chain. The top surface at the front part of the basic member serves as the 25 lower jaw of the gripper. In lateral grooves 89 in the basic member 88 is guided a slide-like member 90, to which a leaf spring 91, forming the upper jaw of the gripper, is fixed by means of the screws 92. A small lever 93 is pivoted at 30 one end to the leaf spring 91 while at its other end it rests in a seat in the basic member 88. By shifting the slide-like member 90 to the rear, that is to say, in the direction of travel of the work-pieces, the leaf spring 91 is also moved back and, 35 at the same time, is opened by the throw of the small lever 93.

The opening and closing of the grippers 83, that is to say, the movement of its slide-like part 90, is effected by means of separately controlled, 40 double-armed levers 94, rotatably mounted on pins 95 on the chain wheels 85 and 87. One arm of each lever 94 is formed as a tooth 96 which, at a given time, runs into a gap or notch 97 in the slide-like member 90. The other arm of the 45 lever 94 carries a bowl 98 which runs round on a fixed cam disc 99 and thereby oscillates the lever 94, so that the tooth 96 of the latter sets the slide 90 in motion, to one side or the other, for opening or closing the gripper.

On both sides of the gripper chain 84, along its path from chain wheel 85 to chain wheel 86 are fixed guide plates or rails 100, at the level of the top surface of the lower jaw of the gripper, the work-pieces engaged by the grippers being 55 supported by these plates.

Within the conveyor path traversed by the gripper chain 84 the following devices for the further treatment of the work-pieces are provided:

1. The folder blades 101, which have a twist of 180 degrees and which turn over on to the body of the work-piece the flaps lying in the direction of travel of said work-piece.
2. The bottom roll 102 with the roll 103 running freely thereon, to press down the folds of the last named flaps.
3. The unfolder guides 104; these are suitably formed rails which engage between the turned over flaps and the body of the work-pieces, and 70 open the flaps again when these flaps have to be subsequently gummed or have to remain open in the finished work-piece.
4. A device for applying the adhesive for sticking the bottom flap, this device consisting of ro- 75

tary adhesive rails 105, which receive the adhesive from the container 106 by way of the dipper roll 107 and the applicer roll 108.

5. A second folder blade 109, which is shaped like the first folder blade 101 and effects the final folding over of the bottom flap.

6. The bottom roll 110 with the roll 111 running freely thereon, to press down and stick the bottom flap.

10. 7. The stacking table 112, upon which the finished work-pieces are stacked, one against another, in upright position.

The manner in which the whole device works is as follows:

15. The intake roll 5 of Fig. 1 is, as can be seen from the foregoing description, a combined friction and suction roll. Its controllable rubber rails 8 exert a rubbing action on the lowermost sheet of the stack of sheets 1, so that they first of all bulge out this lowermost sheet underneath the rest of the stack; only when this has happened does the series of suction openings 27 come into contact with the sheet. In this way the sheet is first bulged out by the rubber rail 8 into the gap formed between the rolls 5 and 6. The suction effect then set up by the suction openings 27 maintains and completes the bulging in such a way that the sheet is certain to be gripped between the rolls 5 and 6 and a fold formed in it.

20. In contradistinction to other known suction folding devices the suction remains effective even when the fold has been produced and has run out from between the rolls 5 and 6; in fact, it is maintained until the work-piece is gripped between the rolls 5 and 30.

25. The action is the same even with the intake roll 5 according to Fig. 3. The difference consists solely in this; that the sheet, in this case, is initially bulged out by the suction openings 28 instead of by rubber rails and is then seized by suction openings 27, as before.

30. Under the action of the rolls 5 and 30 the work-piece is fed bodily into the impact folder pocket, made up of the guide racks 35 and 35' and 35' the stop rail 37, until the edge of the fold previously formed between the rolls 5 and 6 strikes against the said rail 37, which is adjusted according to the size of the work-piece being operated upon. Delivery of the rear or trailing part of the 35 work-piece through the nip of the rolls 5 and 30 still continues after the edge of the fold in the forward or leading part has been arrested by the rail 37; consequently the work-piece is bulged out and the bulge forcibly driven in between the 40 pair of rolls 30, 31, which thereupon form the second fold.

35. The rolls 30, 31 deliver the work-piece to the pair of rolls 42, 43, which is so adjusted that the leading edge of each work-piece encounters one 40 of the sheet steel rails in the roll 42 when such rail is in the groove or channel 55 in the roll 43; thus, at first, the work-piece is not gripped by the rolls 42 and 43 although it is still being delivered by the rolls 30 and 31. As a result, it buckles to some extent, since it is held back at its forward 45 folded edge by the sheet steel rail 54. In this condition it is then ultimately gripped between the rear edge of the groove 55 in the roll 43 (having regard to the direction of rotation of the latter) and the roll 42. In this manner the work-piece is exactly located both temporally and spatially to come into the path of operation of the succeeding tools, so that these take effect on 50 the right parts of the work-piece.

The work-piece running out from the pair of rolls 42, 43 is seized by the pair of conveyor rolls 44, 45 and conducted to the pre-creaser rolls 46, 47 the construction of which has been hereinbefore described. The circular plate-like blades 57 are used both in the production of bags and in the making of envelopes. They are adjustable to correspond to the width of the work-piece as measured at right angles to the direction of travel. On the other hand, the blade 58, running axially 5 of the roll 46 comes into use only in the production of double pockets for photographs and similar work-pieces, which have to be given a preliminary crease or fold, running at right angles to their direction of travel, in the middle, 10 between their two connected pockets.

15. Immediately afterwards the work-piece runs through the pair of rolls 48, 49 which deliver it to the device which applies the adhesive to the lowermost of the two flaps. This consists of 20 the bottom roll 51 and the several devices arranged on the shaft 59 and has already been described herein, as regards its construction and manner of working. This device comes into operation only in the production of bags stuck 25 at the sides or in the middle and for envelopes with high closure gumming, in which there arises the problem of putting the coating of gum, underneath the flap that lies uppermost, on to the sub-30 adjacent flap in a work-piece which is already completely folded over along longitudinal folds lying at right angles to the direction of travel.

35. From the pair of rolls 50, 51, comprising the adhesive applying device, the work-piece comes in between the pair of conveyor rolls 52, 53 which 35 deliver it up to the grippers 83 of the chain 84. Oscillating sheet metal flaps 113 which come down on to the work-piece at a given moment, ensure the said work-piece lying flat down on the bottom jaw of the gripper receiving it, immediately 40 before being gripped by such gripper. The grippers 83 convey the work-pieces, now half finished and already pre-creased at the flaps still to be turned over, through the fold over zone, comprising the folder blades 101. Here the bottom 45 and closure flaps are turned over on to the body of the work-piece and sharply folded by the roll 103 running on the bottom roll 102.

50. Of the now ready folded bottom and closure flaps, the bottom flap in every case but the closure flap only if it is to remain open in the finished work-piece, is opened again by the unfolder guides 104, and the adhesive for sticking the bottom flap is applied by the rotary adhesive rails 105. The second folder blade 109 then again turns 55 over the bottom flap and the roll 111, running on the bottom roll 110, presses the bottom flap firmly on to the body of the work-piece. The now completely finished work-piece is then brought by its gripper 83 on to the stacking table 112 of the 60 collecting device, the grippers 83 letting go at the moment when the leading edge of the work-piece reaches the stacking table 112. In this way, during the operation of the device, the work-pieces range themselves one against another on 65 the stacking table 112, so that a stack of upstanding finished work-pieces is obtained.

70. The whole of the fold intake device, including the pair of rolls 30, 31 and together with the table 3 supporting the input stack 1 and the impact folder pocket 34, 35, 35', 37 is displaceable in the longitudinal direction of the apparatus as a whole, in the manner hereinbefore described. This provision for adjustment serves for varying and adjusting the separation between the pair of rolls 75

30, 31 and the pair of rolls 42, 43 according to the sizes of work-pieces to be produced at the time.

In the drawings the device is depicted as it is used for working up relatively small work-pieces of which two are completed at each revolution of the machine, that is to say, in one revolution of the rolls 42 and 46, as also of the roll 50 and the rotary adhesive applying rails 105. When, however, the work-pieces exceed a certain size, measured in the direction of travel (and this applies, in practice, to all commercial sizes of double pockets), the device must be so readjusted that for each revolution of the machine only one work-piece is finished. To this end the following measures must be adopted:

1. Since the intake roll 5, in contradistinction to the rolls 42, 46, 50 and the adhesive rails 105, executes two revolutions in one revolution of the machine and, consequently must withdraw a sheet from the stack at each revolution when producing the smaller work-pieces but only at every second revolution when producing the larger ones, the bi-partite cam disc 14 (Fig. 5), which controls the rubber rail 8 mounted in the intake roll 5 must be adjusted so that the extent of its raised peripheral zone is a minimum (according to the full lines in Fig. 5), the cam disc must be released from the locking device 21 and the spur wheel 18 must be brought into engagement with the spur wheel 16 so that the intake roll 5 only withdraws a sheet from the stack at every second revolution.

1a. If an intake roll according to Fig. 3 be employed the vacuum control device must be re-set, in a manner which may be assumed to be known, so that the vacuum comes into action in the ducts 22 and 29 and in the suction openings 27 and 28 only at every second revolution of the roll.

2. One of the two aligning rails 54 fitted in the roll 42 is removed.

3. From the device incorporating the roll 50 one of the adhesive rails 64 is removed and the vacuum duct to those arms of the member 65 which lie adjacent to the adhesive rails 64 thus removed is shut off, the corresponding loosening flaps 75 being likewise put out of action.

4. Half of the grippers 83 fixed on the chain 84 are put out of action, so that between every two operative grippers there remains an inoperative one. The cutting out of the grippers, however, is not effected by taking the whole gripper out of the chain assembly but by drawing out and removing the slide-like part 90 to which is attached the leaf spring 91 serving as the upper jaw.

What we claim is:—

1. In a machine for producing bags, pockets, double pockets and envelopes, means for extracting individual work-pieces from a stack of work-pieces carried in the machine and forming two initial parallel folds in each extracted work-piece, said means comprising a pair of intake rolls, one of which, constituted as a suction roll, is adapted to draw a work-piece from the stack into the nip of the intake rolls with simultaneous formation of the first fold, a second pair of rolls, one of which co-operates with the intake suction roll to withdraw the work-pieces from the nip of the intake rolls and a fold receiving pocket positioned to arrest the first fold of the work-piece while the latter is still in process of being fed between the two co-operating rolls of the first and second pairs, said second pair of rolls being adapted to nip the bight thus formed in the work-piece and to extract the work-piece from the fold receiving pocket.

from the fold receiving pocket, with simultaneous formation of the second fold.

2. The device of claim 1, characterized by the fold receiving pocket including adjustable means adapted to determine the position of arrest of the first fold of the work-piece according to the size of the latter and the required distance of separation between the first and second folds.

3. In a machine for producing bags, pockets, double pockets and envelopes, means for extracting individual work-pieces from a stack of work pieces carried in the machine and forming two initial parallel folds in each extracted work-piece, said means comprising a pair of intake rolls, one of said rolls including means for engaging the work-piece to be extracted from the stack and forming a bight therein in the region thereof destined for the first fold and being organized as a suction roll to draw the bight of the work-piece into and through the nip of said intake rolls, with simultaneous formation of said first fold, a second pair of rolls, one of which co-operates with the intake suction roll to withdraw the work-piece from the nip of the intake rolls and a fold receiving pocket positioned to arrest the first fold of the work-piece while the latter is still in process of being fed between the two co-operating rolls of the first and second pairs, said second pair of rolls being adapted to nip the second bight thus formed in the work-piece and to extract the work-piece from the fold receiving pocket, with simultaneous formation of the second fold.

4. In a machine for producing bags, pockets, double pockets and envelopes, means for extracting individual work-pieces from a stack of work-pieces carried in the machine and forming two initial parallel folds in each extracted work-piece, said means comprising a pair of intake rolls, one of said rolls including means adapted frictionally to engage each work-piece and to form a bight there across prior to the extraction of such work-piece from the stack and suction means organized to draw such bight into and through the nip of the intake rolls with simultaneous formation of the first fold, a second pair of rolls one of

which cooperates with the intake roll including the frictional and suction means, to withdraw the work-piece from the nip of the intake rolls and a fold receiving pocket positioned to arrest the first fold of the work-piece while the latter is still in process of being fed between the two co-operating rolls of the first and second pairs, said second pair of rolls being adapted to nip the second bight thus formed in the work-piece and to extract the work-piece from the fold receiving pocket, with simultaneous formation of the second fold.

5. In a machine for producing bags, pockets, double pockets and envelopes, means for extracting individual work-pieces from a stack of work-pieces carried in the machine and forming two initial parallel folds in each extracted work-piece, said means comprising a pair of intake rolls, one of said rolls including suction means organized to engage each work-piece and to form a bight there across prior to the extraction of such work-piece from the stack and further suction means organized to draw such bight into and through the nip of the intake rolls, with simultaneous formation of the first fold, a second pair of rolls, one of which cooperates with the intake roll including the suction means to withdraw the work-piece from the nip of the intake rolls and a fold receiving pocket positioned to arrest the second fold.

first fold of the work-piece while the latter is still in process of being fed between the two co-operating rolls of the first and second pairs, said second pair of rolls being adapted to nip the second bight thus formed in the work-piece and to extract the work-piece from the fold receiving pocket, with simultaneous formation of the second fold.

6. In a machine for producing bags, pockets, 10 double pockets and envelopes in a variety of sizes the combination with an assembly including means for holding a plurality of work-pieces in a stack and means for withdrawing work-pieces from the stack forming two initial longitudinal 15 parallel folds in each work-piece so withdrawn and ejecting the work-piece so folded, and a second assembly including means for receiving the initially folded work-piece ejected by the first assembly and means for producing transverse 20 folds in such work-piece of means for varying the spatial separation between said first mentioned and said second mentioned assemblies.

7. In a machine for producing bags, pockets, 25 double pockets and envelopes in a variety of sizes the combination with an assembly including means for holding a plurality of work-pieces in a stack and means for withdrawing work-pieces from the stack forming two initial longitudinal parallel folds in each work-piece so withdrawn 30 and ejecting the work-piece so folded, and a second assembly including means for receiving and aligning the initially folded work-piece ejected by the first assembly and means for producing transverse folds in such work-piece of means for 35 varying the spatial separation between said first mentioned assembly and the receiving and aligning means of the second mentioned assembly.

8. In a machine for folding and sticking work-pieces to produce bags, pockets, double pockets and envelopes, means for supporting a stack of work-pieces, a pair of intake rolls positioned in proximity to said stack and including means for drawing a work-piece therefrom into their nip with simultaneous formation of a first fold in such 45 work-piece, a pocket structure positioned tangentially to the periphery of one of said intake rolls, and means for guiding the work-piece from the nip of said intake rolls into said pocket structure, the latter including an adjustable 50 resting abutment for said first fold in said work-piece, a second pair of rolls having their nip located opposite the mouth of said pocket structure said second pair of rolls adapted to withdraw said work-piece from said pocket structure with simultaneous formation of a second fold in said 55 work-piece parallel to said first fold, one of said second pair of rolls coacting with one of said intake rolls to maintain feed of said work-piece into the nip of said second pair of rolls during arrest 60 of said first fold by the abutment of said pocket structure, means for producing in the work-piece opposing folds transverse to said first and second folds, means for sticking together flaps resulting from the folding of the work-piece, means 65 for receiving finished work-pieces and means for conveying work-pieces from the nip of the second mentioned pair of rolls past the said transverse fold producing means and the said flap sticking means to said finished work-piece receiving means.

9. In a machine for folding and sticking work-pieces to produce bags, pockets, double pockets and envelopes, means for supporting a stack of work-pieces, a pair of intake rolls positioned in proximity to said stack and including means for

drawing a work-piece therefrom into their nip with simultaneous formation of a first fold in such work-piece, a pocket structure positioned tangentially to the periphery of one of said intake rolls, and means for guiding the work-piece from the nip of said intake rolls into said pocket structure, the latter including an adjustable arresting abutment for said first fold in said work-piece, a second pair of rolls having their nip located opposite the mouth of said pocket structure, said second pair of rolls adapted to withdraw said work-piece from said pocket structure with simultaneous formation of a second fold in said work-piece parallel to said first fold, one of said second pair of rolls coacting with one of said intake rolls to maintain feed of said work-piece into the nip of said second pair of rolls during arrest of said first fold by the abutment of said pocket structure, a roll track conveyor adapted to withdraw the workpiece from the nip of said second mentioned pair of rolls, an endless conveyor including means for gripping individual work-pieces emerging from the roll track conveyor, means associated with the endless conveyor for producing in the work-piece gripped thereon folds transverse to the said first and second folds, means for sticking together predetermined flaps of the work-piece produced by the folding thereof and means for receiving finished work-pieces, said endless conveyor further including means for causing the work-pieces to be engaged by its gripping means when delivered from the roll track and disengaged from such gripping means; upon arrival at the finished work-piece receiving means.

10. A machine according to claim 9, wherein one roll of the first pair of rolls of the roll track conveyor carries axially directed radially projecting aligning means for the second fold of the work-piece, the other roll of said pair being recessed to accommodate said aligning means during rotation of said rolls.

11. A machine according to claim 9, wherein the roll track conveyor includes a pair of co-acting rolls organized for pre-creasing the work-piece on the lines of the transverse folds subsequently to be produced in said work-piece.

12. A machine according to claim 9, wherein the roll track conveyor includes a pair of co-acting rolls organized to produce in the work-piece a crease intermediate the first and second folds and running in the same general direction as said folds.

13. A machine according to claim 9, wherein the roll track conveyor includes a pair of co-acting rolls incorporating means for sticking together overlapping flaps when produced by the forming of the first and second folds in the work-piece.

14. In a mechanism for the automatic production of a fold in an initially flat work-piece, means for supporting a stack of work-pieces, a suction roll and counter roll organized to draw a work-piece from the stack into their nip and there to produce the fold, said suction roll including vacuum means for engaging the work-piece, an axially extending, radially displaceable friction rail adapted for transitory engagement with the work-piece to form therein a bight for subsequent engagement by said vacuum means and means tending to maintain said friction rail within the confines of the suction roll periphery, means for rotating said suction roll and means operative periodically during rotation of said suction roll to protrude said friction rail from its periphery into contact with the work-piece to be engaged.

15. In a mechanism for the automatic production of a fold in an initially flat work-piece, means for supporting a stack of work-pieces, a suction roll and counter roll organized to draw a work-piece from the stack into their nip and there to produce the fold, said suction roll including vacuum means for engaging the work-piece, an axially extending, radially displaceable friction rail adapted for transitory engagement with the work-piece to form therein a bight for subsequent engagement by said vacuum means and means tending to maintain said friction rail within the confines of the suction roll periphery, means for rotating said suction roll, cam means operatively associated with said suction roll and friction rail to protrude said friction rail periodically from the rotating roll periphery into contact with the work-piece and means for varying the number of revolutions executed by the suction roll between successive actuations of said friction rail by said cam means.
16. In a mechanism for the automatic production of a fold in an initially flat work-piece, means for supporting a stack of work-pieces, a suction roll and counter roll organized to draw a work-piece from the stack into their nip and there to produce the fold, a suction roll including vacuum means for engaging the work-piece, an axially extending, radially displaceable friction rail adapted for transitory engagement with the work-piece to form therein a bight for subsequent engagement by said vacuum means and means tending to maintain said friction rail within the confines of the suction roll periphery, means for rotating said suction roll, a cam mounted coaxially with said suction roll and having an operative portion adapted to act on said friction rail to protrude the same from the rotating roll periphery into contact with the work-piece, releasable means for holding said cam stationary during rotation of the suction roll, so as to cause actuation of said friction rail once in every revolution of said suction roll and means operable when said cam holding means is released to rotate said cam in the same direction as the suction roll but at a speed such as to cause the suction roll to execute a plurality of revolutions between successive actuations of the friction rail.
17. The device according to claim 16, characterized by means for varying the period of dwell of the cam relatively to the friction rail.
18. In a machine for folding and sticking work-pieces to produce bags, pockets, double pockets and envelopes, the combination with means for supporting a stack of work-pieces and means for extracting work-pieces one by one from the stack and forming substantially simultaneously, the first longitudinal fold in the extracted work-piece, of means for feeding the work-piece folded edge foremost, means for receiving and arresting the folded part of the work-piece under maintained feed of the opposing non-folded part and initiation of the second longitudinal fold therein by the same feed means, means for withdrawing the work-piece from said receiving and arresting means with simultaneous completion of the said second longitudinal fold, means for receiving finished work-pieces, means for transporting work-pieces from the means which forms the second longitudinal fold to the finished work-piece receiving means and, operatively associated with said work-piece transporting means, means for producing transverse folds in said work-piece and transverse flap sticking means.
19. In a machine for folding and sticking work-pieces to produce bags, pockets, double pockets and envelopes, the combination with means for supporting a stack of work-pieces and means for extracting work-pieces one by one from the stack and forming, substantially simultaneously, the first longitudinal fold in the extracted work-piece, of means for feeding the work-piece folded edge foremost, means for receiving and arresting the folded part of the work-piece under maintained feed of the opposing non-folded part and initiation of the second longitudinal fold therein by the same feed means, means for withdrawing the work-piece from said receiving and arresting means with simultaneous completion of the said second longitudinal fold, means for receiving finished work-pieces, means for transporting work-pieces from the means which forms the second longitudinal fold to the finished work-piece receiving means and, operatively associated with said work-piece transporting means, means for producing transverse folds in said work-piece and transverse flap sticking means.
20. In a machine for folding and sticking work-pieces to produce bags, pockets, double pockets and envelopes, the combination with means for supporting a stack of work-pieces and means for extracting work-pieces one by one from the stack and forming, substantially simultaneously, the first longitudinal fold in the extracted work-piece, of means for feeding the work-piece folded edge foremost, means for receiving and arresting the folded part of the work-piece under maintained feed of the opposing non-folded part and initiation of the second longitudinal fold therein by the same feed means, means for withdrawing the work-piece from said receiving and arresting means with simultaneous completion of the said second longitudinal fold, means for receiving finished work-pieces, means for transporting work-pieces from the means which forms the second longitudinal fold to the finished work-piece receiving means and, operatively associated with said work-piece transporting means, means for producing transverse folds in said work-piece and transverse flap sticking means.
21. In a machine for folding and sticking work-pieces to produce bags, pockets, double pockets and envelopes, the combination with means for supporting a stack of work-pieces and means for extracting work-pieces one by one from the stack and forming, substantially simultaneously, the first longitudinal fold in the extracted work-piece, of means for feeding the work-piece folded edge foremost, means for receiving and arresting the folded part of the work-piece under maintained feed of the opposing non-folded part and initiation of the second longitudinal fold therein by the same feed means, means for withdrawing the work-piece from said receiving and arresting means with simultaneous completion of the said second longitudinal fold, means for receiving finished work-pieces, means for transporting work-pieces from the means which forms the second longitudinal fold to the finished work-piece receiving means and, operatively associated with said work-piece transporting means, means for producing transverse folds in said work-piece and transverse flap sticking means.

porting means, means adaptable, when producing bag-like articles, for introducing adhesive between already contacting overlapping longitudinal flaps and sticking said flaps together, means for producing transverse folds in said work-piece and transverse flap sticking means.

22. In a machine for folding and sticking work-pieces to produce bags, pockets, double pockets and envelopes, the combination with means for supporting a stack of work-pieces and means for extracting work-pieces one by one from the stack and forming, substantially simultaneously, the first longitudinal fold in the extracted work-piece, of means for feeding the work-pieces folded edge foremost, means for receiving and arresting the folded part of the work-piece under maintained feed of the opposing non-folded part and initiation of the second longitudinal fold therein by the same feed means, means for withdrawing the work-piece from said receiving and arresting means with simultaneous completion of the said second longitudinal fold, means for receiving finished work-pieces, means for transporting work-pieces from the means which forms the second longitudinal fold to the finished work-piece receiving means and, operatively associated with said work-piece transporting means, means adapted to pre-crease work-pieces for transverse folding, means adaptable, when producing bag-like articles, for introducing adhesive between already contacting overlapping longitudinal flaps and sticking said flaps together, means for producing transverse folds in said work-piece and transverse flap sticking means.

23. In a machine for folding and sticking work-pieces to produce bags, pockets, double pockets and envelopes, the combination with means for supporting a stack of work-pieces and means for extracting work-pieces one by one from the stack and forming, substantially simultaneously, the first longitudinal fold in the extracted work-piece, of means for feeding the work-piece folded edge foremost, means for receiving and arresting the folded part of the work-piece under maintained feed of the opposing non-folded part and initiation of the second longitudinal fold therein by the same feed means, means for withdrawing the work-piece from said receiving and arresting means with simultaneous completion of the said second longitudinal fold, means for receiving finished work-pieces, means for transporting work-pieces from the means which forms the second longitudinal fold to the finished work-piece receiving means and, operatively associated with said work-piece transporting means, means adapted to pre-crease work-pieces for transverse folding and adaptable to produce in double pocket work-pieces a longitudinal crease intermediate the first and second longitudinal folds, means adaptable, when producing bag-like articles, for introducing adhesive between already contacting overlapping longitudinal flaps and sticking said flaps together, means for producing transverse folds in said work-piece and transverse flap sticking means.

24. The machine according to claim 18, characterized by the work-piece transporting means including feed means operative temporarily, before feeding, to arrest progress of the leading folded edge of the work-piece directly upon its emergence from the means completing the second longitudinal fold and thereby to align said work-piece prior to initiation of the transverse folds.

25. In a machine for folding and sticking work-

pieces to produce bags, pockets, double pockets and envelopes, the combination comprising means for supporting a stack of work-pieces, means for extracting work-pieces, one by one from the stack with substantially simultaneous formation of the first longitudinal fold in the extracted work-piece, means for feeding the work-piece, folded edge foremost, means for receiving and arresting the folded part of the work-piece under maintained positive feed of its non-folded part and initiation of the second longitudinal fold therein by the same feed means, means for withdrawing the work-piece from said receiving and arresting means with simultaneous completion of the said second longitudinal fold, rotary means adapted to feed the work-piece in a direction at right angles to the longitudinal folds, said rotary means embodying means for aligning the work-piece means for pre-creasing the work-piece at the predetermined locations for transverse folding and means adaptable for sticking together already overlapping longitudinal flaps, endless conveyor means arranged to receive work-pieces from the aforesaid rotary means, said endless conveyor means being associated with means for folding the transverse flaps and means for sticking down said transverse flaps, and means adapted to receive finished work-pieces from said endless conveyor means.

26. In a machine for folding and sticking work-pieces to produce bags, pockets, double pockets and envelopes, the combination comprising means for supporting a stack of work-pieces, means for extracting work-pieces, one by one from the stack with substantially simultaneous formation of the first longitudinal fold in the extracted work-piece, means for feeding the work-piece, folded edge foremost, means for receiving and arresting the folded part of the work-piece under maintained positive feed of its non-folded part and initiation of the second longitudinal fold therein by the same feed means, means for withdrawing the work-piece from said receiving and arresting means with simultaneous completion of the said second longitudinal fold, rotary means adapted to feed the work-piece in a direction at right angles to the longitudinal folds, said rotary means embodying means for aligning the work-piece means for pre-creasing the work-piece at the predetermined locations for transverse folding, means operable when producing double pockets and like folders to form a longitudinal crease at a predetermined location intermediate between the already existing longitudinal folds and means operable when producing bag-like articles to stick together already overlapping longitudinal flaps, endless conveyor means arranged to receive work-pieces from the aforesaid rotary means, said endless conveyor means being associated with means for folding the transverse flaps and means for sticking down said transverse flaps, and means adapted to receive finished work-pieces from said endless conveyor means.

27. In a machine for folding and sticking work-pieces to produce bags, pockets, double pockets and envelopes, means for supporting a stack of work-pieces, means for extracting single work-pieces from the stack with simultaneous formation of a first longitudinal fold, means for immediate subsequent formation of a second longitudinal fold, rotary means adapted to receive the longitudinally folded work-pieces from the means producing the second longitudinal fold and to impart to said work-pieces a translatory movement in a direction transverse to their longi-

- 5 tudinal folds while preparing said work-pieces for transverse folding, endless conveyor means adapted to receive the prepared work-pieces from said rotary means, transverse folder means and trans-
 10 5 verse flap sticking means associated with said endless conveyor means and means for receiving finished work-pieces from said endless conveyor means, said rotary means including means for sticking together overlapping flaps produced in work-pieces for bags and bag-type envelopes by the initial longitudinal folding of such work-pieces.
- 15 28. In a machine for folding and sticking work-pieces to produce bags, pockets, double pockets and envelopes, means for supporting a stack of work-pieces, means for extracting single work-pieces from the stack with simultaneous formation of a first longitudinal fold, means for immediate subsequent formation of a second lon-
 20 15 gitudinal fold, rotary means adapted to receive the longitudinally folded work-pieces from the means producing the second longitudinal fold and to impart to said work-pieces a translatory movement in a direction transverse to their lon-
 25 20 gitudinal folds while preparing said work-pieces for transverse folding, endless conveyor means adapted to receive the prepared work-pieces from said rotary means, transverse folder means and transverse flap sticking means associated with said endless conveyor means and means for re-
 30 25 ceiving finished work-pieces from said endless conveyor means, said rotary means including means for temporarily separating overlapping flaps produced in work-pieces for bags and bag-
 35 30 type envelopes by the initial longitudinal folding of such work-pieces, means for coating adhesive on to the surfaces of the lower longitudinal flaps exposed by the temporary separation of the upper longitudinal flaps therefrom and means for bring-
 40 35 ing said upper longitudinal flaps into adhesive contact with the coated surfaces of said lower longitudinal flaps.
- 45 29. In a machine for folding and sticking work-pieces to produce bags, pockets, double pockets and envelopes, means for supporting a stack of work-pieces, means for extracting single work-pieces from the stack with simultaneous forma-
 50 45 tion of a first longitudinal fold, means for im-
 55 50 mediate subsequent formation of a second lon-
 60 55 gitudinal fold, rotary means adapted to receive the longitudinally folded work-pieces from the means producing the second longitudinal fold and to impart to said work-pieces a translatory movement, in a direction transverse to their lon-
 65 60 gitudinal folds while preparing said work-pieces for transverse folding, endless conveyor means adapted to receive the prepared work-pieces from said rotary means, transverse folder means and transverse flap sticking means asso-
 70 65 ciated with said endless conveyor means and means for receiving finished work-pieces from said endless conveyor means, said rotary means including means for uniting overlapping flaps produced by the longitudinal folding of work-
 75 70 pieces for bags and bag-type envelopes, which last named means comprise a pair of rotary mem-
 75 75 bers adapted to feed a work-piece between them, one of said rotary members being a driving mem-
 ber, and suction means and adhesive applying means associated with said driving member to partake in the uniform rotation thereof, said suction means being organized to raise the upper one of the overlapping longitudinal flaps tempor-
 75 75 arily from the subjacent lower longitudinal flap in the work-piece in transit between said

rotary members and said adhesive applying means being organized to enter beneath the tem-
 5 porarily raised upper longitudinal flap, to apply adhesive to the lower longitudinal flap and to emerge from between the said flaps before the temporary raising of the said upper flap by the suction means is terminated.

30. In a machine for folding and sticking work-pieces to produce bags, pockets, double pockets and envelopes, means for supporting a stack of work-pieces, means for extracting single work-pieces from the stack with simultaneous forma-
 10 30 tion of a first longitudinal fold, means for immediate subsequent formation of a second lon-
 15 35 gitudinal fold, rotary means adapted to receive the longitudinally folded work-pieces from the means producing the second longitudinal fold and to impart to said work-pieces a translatory movement in a direction transverse to their lon-
 20 40 gitudinal folds while preparing said work-pieces for transverse folding, endless conveyor means adapted to receive the prepared work-pieces from said rotary means, transverse folder means and transverse flap sticking means associated with said endless conveyor means and means for re-
 25 45 ceiving finished work-pieces from said endless conveyor means, said rotary means including means for uniting overlapping flaps produced by the longitudinal folding of work-pieces for bags and bag-type envelopes, which last named means comprises a pair of rotary members adapted to feed the work-pieces between them, one of said rotary members being a driving member, suction means organized for temporarily raising the upper one of said overlapping longitudinal flaps from the subjacent lower longitudinal flap in a work-
 30 50 piece in transit between said rotary members, means for applying adhesive to the lower longitudinal flap while the upper longitudinal flap is raised, said suction means and said adhesive applying means partaking in the uniform rotation of said driving member, and means for imparting to said suction means and to said adhesive applying means, a varying velocity which, for the raising of the upper longitudinal flap and the application of adhesive to the lower longitudinal flap, is higher than the velocity of feed of the work-piece but, for recession of the adhesive applying means and lowering of the upper longitudinal flap on to the adhesive-coated surface of the lower longitudinal flap, becomes lower than said feed velocity of said work-pieces.

35 55 31. In a machine for folding and sticking work-pieces to produce bags, pockets, double pockets and envelopes, means for supporting a stack of work-pieces, means for extracting single work-pieces from the stack with simultaneous forma-
 40 60 tion of a first longitudinal fold, means for im-
 45 65 mediate subsequent formation of a second lon-
 50 70 gitudinal fold, rotary means adapted to receive the longitudinally folded work-pieces from the means producing the second longitudinal fold and to impart to said work-pieces a translatory movement in a direction transverse to their lon-
 55 75 gitudinal folds while preparing said work-pieces for transverse folding, endless conveyor means adapted to receive the prepared work-pieces from said rotary means, transverse folder means and transverse flap sticking means associated with said endless conveyor means and means for re-
 60 80 ceiving finished work-pieces from said endless conveyor means, said rotary means including means for uniting overlapping flaps produced by the longitudinal folding of work-pieces for bags and bag-type envelopes, which last named means

comprises a pair of rotary members adapted to feed the work-pieces between them, one of said rotary members being a driving member, suction means organized for temporarily raising 5 the upper one of said overlapping longitudinal flaps from the subjacent lower longitudinal flap in a work-piece in transit between said rotary members, means for applying a coating of adhesive to the lower longitudinal flap while the 10 upper longitudinal flap is raised, means for separating said lower longitudinal flap from said adhesive applying means after application of said adhesive coating, said suction means, adhesive applying means and lower flap separating 15 means partaking in the uniform rotation of said driving member, and means for imparting to said suction means, said adhesive applying means and said lower flap separating means a varying velocity which, for the raising of said upper flap 20 and the application of the adhesive coating to said lower flap, is higher than the velocity of feed of the work-piece but, for separation of said lower flap from the adhesive applying means, recession of said adhesive applying means and 25 lowering of said upper flap on to the adhesive-coated surface of said lower flap, becomes lower than said feed velocity of said work-piece.

32. The device according to claim 31, characterized by the said lower flap separating means

including an element movable into contact with the lower longitudinal flap of the work-piece behind the adhesive applying means, means operative to maintain said element out of contact with said lower flap during application of the adhesive coating thereto and means operative to press said element on to said lower flap during recession of said adhesive applying means from said lower flap.

33. In a machine for folding and sticking work-pieces to produce bags, pockets, double pockets and envelopes, means for supporting a stack of work-pieces, means for extracting single work-pieces from the stack with simultaneous formation of a first longitudinal fold, means for immediate subsequent formation of a second longitudinal fold, rotary means including a pair of coating rotary feed members adapted temporarily to arrest and align work-pieces received from the means forming the second longitudinal fold, before imparting feed movement to such work-pieces, endless conveyor means adapted to receive the prepared work-pieces from said rotary means, transverse folder means and transverse flap sticking means associated with said endless conveyor means and means for receiving finished work-pieces from said endless conveyor means.
